UNITED STATES PATENT OFFICE.

CHARLES SMITH, OF BUFFALO, NEW YORK.

IMPROVED HAIR-RESTORER.

Specification forming part of Letters Patent No. 41,791, dated March 1, 1864.

To all whom it may concern:

Be it known that I, CHARLES SMITH, of the city of Buffalo, county of Erie, and State of New York, have invented or discovered a new and Improved Composition for the Hair to be Used as a Hair-Restorer; and I do hereby declare that the following is a full and exact description thereof, to wit:

The said composition is made of seven ingredients, used about in the following proportions—say for a quantity sufficient to fill one hundred bottels of two gills each: Take fifteen pounds of burdock-root, one pint of Peruvian wound-balsam, one-half pint lemon-juice, five pints of best castor-oil, five pints (ninety-five per cent.) alcohol, one ounce oil of rose, three gallons of rain-water. Thoroughly mix these

ingredients together, substantially in the proportions as described, and it makes an excellent compound for the hair. The bottle should be thoroughly shaken before the composition is put on the hair, and it may be used pretty freely once a day, and it should be well rubbed into the scalp. Keep the bottle in which it is contained air-tight and not too warm.

I claim—

A composition for the hair, compounded of the ingredients substantially as herein described.

C. SMITH.
